PAGE 3

Fig. 3

Fig. 4

Fig. 5

Figure 1 is a front elevational view of a toy radio station embodying my new design;

Figure 2 is a front perspective view from one end thereof;

Figure 3 is a rear perspective view from the other end thereof;

Figure 4 is a fragmentary top plan view thereof, with the microphone omitted for illustrative purposes only; and

Figure 5 is a fragmentary bottom plan view thereof, with the microphone omitted for illustrative purposes only.

I claim:

The ornamental design for a toy radio station, as shown and described.
